CLAIM

The ornamental design for a display device with graphical user interface, as shown and described.

DESCRIPTION

FIG. 1 is a front view of a first image in a sequence for a display device with graphical user interface; and, FIG. 2 is a front view of a second image thereof.

The appearance of the transitional image sequentially transitions between the images shown in FIGS. 1-2. The process or period in which one image transitions to another image forms no part of the claimed design.

The broken lines in the figures showing a display screen, electronic device, and portions of the graphical user interface are for illustrative purposes only and form no part of the claimed design.
